PORTABLE STEAM GENERATOR

Julius K. Sebo, New York, N. Y.

Application October 25, 1939, Serial No. 301,106

10 Claims. (Cl. 219—38)

This invention relates to steam generators, and particularly to portable steam generator units adapted for the purpose of supplying steam for pressing irons, steaming appliances employed in the treatment of fur, and for a variety of other uses.

It has been found that most portable devices of this category are of extremely limited capacities, due to the fact that they must of necessity be of sufficiently reduced proportions to render them conveniently portable, and because of such limitations it has frequently been found preferable to employ the larger and less convenient stationary generators. It is primarily within the contemplation of my invention to improve upon existing devices of this class by providing a portable generator with a sufficiently large steam generating capacity for all practical purposes. And in this aspect of my invention it is another object to generate only such quantities of steam as are normally required by the consuming appliances, an objective which I attain by heating a comparatively small volume of water in a chamber separate and apart from the main water storage chamber but suitably connected thereto by a water feed line of restricted proportions. In this manner I provide against the generation of excessive quantities of steam, such as occurs in certain conventional structures where all the stored water is heated and the resulting steam caused to be partially wasted by being directed into the atmosphere through safety valves or returned to the storage and generating chamber in the form of a condensate. And by means of my invention I accomplish the further purpose of obviating the danger of excessively high steam velocities in the steam-consuming appliance, such as frequently occurs where there is an uncontrolled generation of large quantities of steam.

It is another object of my invention to effectuate a controlled generation of steam, and to further obviate the danger of extremely wet steam or hot particles of water from being ejected from the unit. And in this aspect of my invention it is another object to provide efficient means to separate globules of water from the steam.

It is a further object of my invention to provide means for assuring the electric heating element a long life by enabling it to remain immersed in water even after the main water storage chamber has run dry.

A further object of my invention is to provide convenient means for collecting and removing any sediment which may collect in the main water storage chamber.

And it is still a further object of my invention to utilize certain of the structural elements intended for accomplishing some of the aforesaid purposes, as supports for the wheeled under-structure of this apparatus.

Other objects, features and advantages will appear from the drawings and the description hereinafter given.

Referring to the drawings,

Figure 1 is a side elevation of the apparatus 5 of my invention.

Figure 2 is a plan view of the structure of Figure 1.

Figure 3 is a section of Figure 1 taken along 10 line 3—3.

Figure 4 is a section of Figure 2 taken along line 4—4.

Figure 5 is a section, in reduced proportions, of Figure 4 taken along line 5—5 thereof, and

Figure 6 is a section of Figure 1 taken along 15 line 6—6.

In the drawings there are illustrated three intercommunicating chambers, namely the primary chamber 10 for storing the water to be heated, the intermediate chamber 11 wherein the steam 20 is generated, and the outlet chamber 12 serving both as a receptacle for the generated steam prior to being fed to the consuming device and also as a steam separator.

The primary chamber 10 is provided with a 25 water inlet 13 controlled by a valve 14 of conventional structure. Extending from the bottom floor 15 of chamber 10 to the lowermost portion 16 of chamber 11 is the feed water pipe 17 of restricted proportions to permit a gradual flow 30 of water from chamber 10 to chamber 11. It will be noted that the said lowermost portion 16 is disposed below the level of floor 15 of chamber 10 thereby rendering it possible for said lowermost portion to contain water even after chamber 35 10 has run dry. Positioned within said lowermost portion 16 is the electric heating element 17 disposed substantially along the entire extent thereof. As will be noted from Figure 5, said heating element is secured by screws 18 to the 40 wall 19 of compartment 20. Positioned within said compartment are the binding posts 21 electrically connected in conventional manner to the heating element 17. Attached to said binding posts are the electrical conductors 22 which extend through flexible tubing 23 to the switch member 24 mounted on a wall of chamber 10. Electrically connected to said switch are the wall plug 25 and connection 26 for attachment to a 45 pressing iron or any other steam-consuming appliance. The construction of the switch 24 is of conventional nature and hence will not be set forth in further detail.

Communicating between the upper portions of the primary and intermediate chambers is the 55 breather pipe 27 which is adapted to equalize the pressures within said two chambers. By this means no excessive pressures can be developed within intermediate chamber 11 to cause a back pressure through line 17 into chamber 10; and 60

furthermore, chamber 10 will at times be provided with a positive pressure, under the influence of steam passing through pipe 27, for assuring a positive and continuous movement of the feed water through line 17.

The top of the intermediate chamber 11 has extending therefrom the steam pipe 28 communicating with the upper portion of outlet chamber 12, the latter chamber being provided at the top 10 thereof with an outlet fitting 29 adapted for attachment to any suitable hose or pipe connected with a steam-consuming device. The portion of outlet chamber 12 below pipe 28 is adapted to receive any condensate or globules of water from 15 said pipe 28, the lighter steam passing up through fitting 29 whereas the heavier water particles are separated by gravity to accumulate in the lower portion of chamber 12. A pet cock 30 is provided at the bottom of chamber 12 to enable any excessive accumulation of condensate to be drawn off.

It will be noted that primary and intermediate chambers 10 and 11 are in spaced relation, being separated by the space 31 therebetween. The 25 primary chamber 10 contains the boss 32 extending into said space; and in engagement with the lateral periphery of said boss are the spacing lugs 33 extending transversely across said space 31. The chamber 11 is also supported through the 30 medium of bolt 34 extending from the boss 35 in the casing of chamber 10 into the boss 36 extending transversely from chamber 11 through space 31.

The bottom floor 15 of chamber 10, illustrated 35 as sloping rearwardly towards the depressed portion 37 of the chamber, is adapted to receive any sediment which may collect therein. The removable plate 38 will enable any such accumulated sediment to be readily removed.

40 It will further be observed that advantage is taken in this invention of the relative positions of depressed portion 37 of chamber 10 and the lowermost portion 16 of chamber 11, to enable such portions to constitute structural supports for 45 the wheeled under-carriage of this device. Thus the wheels 39 are suitably supported and disposed so as to render the entire apparatus readily portable.

As is obvious from the construction hereinabove 50 described, only a small portion of the total water contained in this apparatus is subjected to the direct heating effects of the heating element 17, this portion being contained within the intermediate chamber 11. Hence the relatively small 55 quantity of water contained in the intermediate chamber will be more readily transformed into steam than would be the case if all the water contained in both chambers 10 and 11 were heated. This not only effects a saving in electric 60 current consumption, but also enables the generation of relatively small volumes of steam sufficient for the requirements of the usual steam-consuming devices intended for operative use with such an apparatus. The velocities of steam flow- 65 ing through pipes 28 and 29 are also accordingly relatively low, thereby preventing sputtering and excessive pressures. Although a safety valve 40 is provided in the intermediate chamber 11, it has been found through actual practice that there is 70 much less occasion for such valve to open than in an apparatus where steam is being generated from the entire body of water contained therein. And inasmuch as the quantities of water within 75 intermediate chamber 11 are, as aforesaid, relatively small, it is also obvious that the effect of

the heating element thereon can be readily controlled in accordance with circumstances.

It is of importance, in accordance with the preferred practice of this invention, that the chambers 10 and 11 be insulated from each other, such 5 as by the air space 31. This enables the water in the primary chamber 10 to remain cool and practically unaffected by the heat within chamber 11, thereby assuring relatively cool water being admitted into chamber 11. It has been found that 10 by this arrangement overheating of the water in chamber 11 is prevented, inasmuch as the only source of heating is the readily controllable heating element 17. The resultant steam is hence generally drier than that otherwise produced. 15

The other appurtenances on this apparatus are of a more or less conventional nature including a handle 41, a supporting brace 42 for chamber 12 extending from intermediate chamber 11, a steam gage 43 and a water indicator 44. 20

It is of course understood that the various embodiments above-described and shown in the drawings are illustrative of my invention and not employed by way of limitation, inasmuch as numerous changes and modifications may be made 25 within the scope of the appended claims without departing from the spirit of this invention.

What I claim is:

1. A portable steam generating unit of the class described comprising a system of three intercommunicating combination water and steam reservoirs including a primary, an intermediate and an outlet chamber, a water inlet for the primary chamber, a water feed line communicating between the lower portions of said primary and intermediate chambers, a steam feed line communicating between the upper portions of said intermediate and outlet chambers, conduit means between the upper portions of said primary and intermediate chambers, a steam outlet at the upper portion of the outlet chamber, and an electric heating element at the lower portion of the intermediate chamber, the primary and intermediate chambers being in adjacent spaced relation. 40

2. A portable steam generating unit of the class described comprising a system of three intercommunicating combination water and steam reservoirs including a primary, an intermediate and an outlet chamber, the lowermost portion of said intermediate chamber extending below the bottom of the primary chamber and the upper portion of the intermediate chamber extending above the bottom of the primary chamber, a water inlet for the primary chamber, a water feed line communicating between the bottom of the primary chamber and the said lowermost portion of the intermediate chamber, a steam feed line communicating between the upper portions of said intermediate and outlet chambers, conduit means between the upper portions of said primary and intermediate chambers, a steam outlet at the upper portion of the outlet chamber, and an electric heating element in said lowermost portion of the intermediate chamber, the primary and intermediate chambers being in adjacent spaced relation. 50

3. A portable steam generator of the class described according to claim 2, the said outlet chamber extending from a predetermined level below the top of the intermediate chamber to a predetermined point thereabove. 60

4. In a portable steam generating unit of the class described, a system of three intercommunicating combination water and steam reservoirs 65

- including a primary, an intermediate and an outlet chamber, the lowermost portion of said intermediate chamber extending below the bottom of the primary chamber and the upper portion of the intermediate chamber extending above the bottom of the primary chamber, a water inlet for the primary chamber, a water feed line of reduced proportions communicating between the bottom of the primary chamber and the said lowermost portion of the intermediate chamber for permitting a restricted flow through said feed line, said intermediate chamber independently communicating with the upper portions of the primary and outlet chambers, respectively, an electric heating element in said lowermost portion of the intermediate chamber, the primary and intermediate chambers being in closely spaced relation, a supporting member extending from the primary to the intermediate chamber through the space therebetween, a boss on the primary chamber extending into the space between the primary and intermediate chambers, and spacing lugs on the intermediate chamber extending through said space into engagement with the lateral wall of the boss for maintaining the primary and intermediate chambers in spaced relation.
5. A portable steam generating unit of the class described comprising a system of three intercommunicating combination water and steam reservoirs including a primary, an intermediate and an outlet chamber, a water inlet for the primary chamber, a water feed line communicating between the lower portions of said primary and intermediate chambers, a steam feed line communicating between the upper portions of said intermediate and outlet chambers, conduit means between the upper portions of said primary and intermediate chambers, a steam outlet at the upper portion of the outlet chamber, and an electric heating element at the lower portion of the intermediate chamber, the intermediate chamber being closely spaced from the primary chamber and supported thereby, and the outlet chamber being closely spaced from the intermediate chamber and supported thereby.
6. A portable steam generating unit of the class described comprising a system of three intercommunicating combination water and steam reservoirs including a primary, an intermediate and an outlet chamber, a water inlet for the primary chamber, a water feed line communicating between the lower portion of said primary and intermediate chambers, a steam feed line communicating between the upper portions of said intermediate and outlet chambers, relatively short conduit means between the upper portion of said primary and intermediate chambers, a steam outlet at the upper portion of the outlet chamber, an electric heating element at the lower portion of the intermediate chamber, supporting means extending from the primary chamber and in supporting engagement with the intermediate chamber, and spacing means extending between the primary and intermediate chambers for maintaining them in adjacent spaced relation.
7. In a portable steam generating unit of the class described, a system of three intercommunicating combination water and steam reservoirs including a primary, an intermediate and an outlet chamber, the lowermost portion of said intermediate chamber extending below the bottom of the primary chamber and the upper portion of the intermediate chamber extending above the bottom of the primary chamber, a water inlet for the primary chamber, a water feed line communicating between the bottom of the primary chamber and the said lowermost portion of the intermediate chamber.
8. In a portable steam generator according to claim 7, a pipe extending through the space between the primary and intermediate chambers and constituting the means of communication between said two chambers whereby substantially equal pressures will be maintained therein.
9. A portable steam generating unit of the class described comprising a system of three intercommunicating combination water and steam reservoirs including a primary, an intermediate and an outlet chamber, the lowermost portion of said intermediate chamber extending below the bottom of the primary chamber and the upper portion of the intermediate chamber extending above the bottom of the primary chamber, a water inlet for the primary chamber, a water feed line communicating between the bottom of the primary chamber and the said lowermost portion of the intermediate chamber, a steam feed line communicating between the upper portions of said intermediate and outlet chambers, conduit means between the upper portion of said primary and intermediate chambers, a steam outlet at the upper portion of the outlet chamber, and an electric heating element in said lowermost portion of the intermediate chamber, the primary and intermediate chambers being in closely spaced relation and in supporting engagement with each other, the primary chamber containing a downwardly sloping floor and a depressed portion communicating therewith for receiving accumulated sediment.
10. A portable steam generating unit of the class described comprising a system of three intercommunicating combination water and steam reservoirs including a primary, an intermediate and an outlet chamber, the lowermost portion of said intermediate chamber extending below the bottom of the primary chamber and the upper portion of the intermediate chamber extending above the bottom of the primary chamber, a water inlet for the primary chamber, a water feed line communicating between the bottom of the primary chamber and the said lowermost portion of the intermediate chamber, a steam feed line communicating between the upper portions of said intermediate and outlet chambers, conduit means between the upper portion of said primary and intermediate chambers, a steam outlet at the upper portion of the outlet chamber, and an electric heating element in said lowermost portion of the intermediate chamber, the primary and intermediate chambers being in closely spaced relation, the primary chamber containing a depressed portion in spaced relation to the said lowermost portion of the intermediate chamber, and wheeled means mounted upon the undersides of said lowermost and depressed portions.
